UNITED STATES PATENT OFFICE.

EDWARD C. JONES, OF KANSAS CITY, MISSOURI, ASSIGNOR OF ONE-HALF
TO RICHARD HIRTZ, OF DODGE CITY, KANSAS.

CLASP.

SPECIFICATION forming part of Letters Patent No. 379,229, dated March 13, 1883.

Application filed July 18, 1887. Serial No. 244,573. (No model.)

To all whom it may concern:

Be it known that I, EDWARD C. JONES, a citizen of the United States, residing at Kansas City, in the county of Jackson and State of Missouri, have invented certain new and useful Improvements in Locking-Clasps for Wearing-Apparel; and I do hereby declare that the following is a full, clear, and exact description thereof, which will enable others to make and use the same, reference being had to the accompanying drawings, forming a part of this specification.

The object of my invention is to provide a locking grip-clasp for cuffs, neckties, and other wearing-apparel which may be attached directly to the underwear or intermediately to the ordinary suspender, and will retain its hold effectually upon the fabric, and when strain is exerted increase the power of the grip and lessen the liability of tearing the fabric; and it consists in the novel construction and combination of parts hereinafter fully described, and specifically pointed out in the claims.

In the drawings, Figure 1 is a longitudinal side view of the clasp, showing the jaws in an open position and the cam in an upright position. Fig. 2 is a plan view of the clasp in the position as shown in Fig. 1, showing the slot and perforation to receive the locking-pin. Fig. 3 is a side view of the clasp in a closed position. Fig. 4 shows in side view an alternate form of construction to that shown in Fig. 1. Fig. 5 is an edge view of a clasp, showing the projections turned backward. Fig. 6 is a detail view of the cam.

In the construction of my improved clasp I have designed the same to be adapted to various uses, the most applicable of which are to garments or articles of personal wear usually unsupported upon the wearer and which cannot be kept in place securely, and for this purpose I make the clasp preferably from steel and consisting of two longitudinal flat strips or plates, a a' , narrow in width. One of said strips or plates, a , which in use will lie outwardly, I make longer than the strip or plate a' . On the strip a' , I make on opposite longitudinal edges, midway its length, the ears a^2 a^3 , which are turned upwardly in a vertical relation to flat surface of the strip a' , and perforated in a transverse relation, the perforations

being made close to the surface of the strip. I then place the strips a a' flatwise together, the strip a lying between the ears a^2 a^3 , and one end of each strip a a' made to extend in one direction nearly a corresponding length. I then insert a rivet, a^4 , through the opposite end of the strip a' and also through the strip a . Transversely through the outer strip, a , extending from a point above the ears a^2 a^3 in the direction of the jaws of the grip, I make a slot, a^5 , which extends nearly one-half the distance described by the jaws of the grip and is slightly decreased in width toward said free ends. I then punch with a proper instrument the depressions a^6 in the outer surfaces of each strip a a' along the free ends of the jaws sufficient to give grip to the clasp, leaving the points a^7 upon the opposite inner sides of the said free ends or jaws of the clasp A . I then cut from a flat piece of metal a cam-lever, B , which is constructed as follows: The lower portion, b , is of a width equal to the space between the opposite ears a^2 a^3 , and extends in height a distance above the said ears sufficient to throw the jaws of the clasp apart from a closed position, which is accomplished by the shoulders b' b' , which strike against the inner sides of the strip a . The portion b^2 of the cam-lever which joins the cam b is of a width equal to that of the slot at the point above the ears a^2 a^3 , and is contracted in width toward the extreme end.

At a point midway between the ears a^2 a^3 and the extreme free ends of the jaws or strips a a' , I make through said plate or strip a the perforation a^8 , and through the plate or strip a' a similar perforation, a^9 , corresponding in a vertical relation with the perforation a^8 , is so punched as to leave a depression on the opposite side of the plate a' .

On the lower and outer edges of the portion b of the cam-lever B , I affix the pivots b^3 b^3 , which are placed in the perforation in the ears a^2 a^3 . I then attach rigidly to the portion b^2 , on the inner side of the cam-lever B , a pin, b^4 , which is slightly tapered at the point in a downward direction and enters the perforations a^8 a^9 when the lever is thrown down. The portion b^2 of the cam-lever is inserted through the slot a^5 in the plate or strip a , so as to oscillate therein and when upright bear

against the plate a within the limits of slot a^5 . I then bend the upper plate or strip, a , a slight distance upwardly at an angle from the pivot a^4 to the jaw of the clasp, and from that point 5 to the end of the jaw in a horizontal relation.

The extreme end of the lever B is made with a curved end, b^5 , so as to give room for the lifting of the lever and the removal of the fabric from the jaws. The cam-lever B is also 10 bent slightly forward at the point b^6 , which permits the lever to lie flatwise upon the plate a when the fabric is between the jaws of the clasp. The end of the plate or strip a is continued in a direction opposite to the jaws of 15 the grip a slight distance from the rivet a^4 and then bent at right angle, and a button, C, pivotally secured to said end of the strip a .

Instead of riveting the upper and lower strips or plates, a a' , together, as in Fig. 1, I 20 may stamp the said plates in one piece and bend one upon another, forming a loop, a^{10} , at the end, which is given the tension of a spring.

The portion of the wearing-apparel which it 25 is desired to support is introduced between the jaws a a' of the clasp when in the position seen in Fig. 1—as, for instance, when used for a cuff-holder the sleeve portion of the under-wear will be inserted, and upon pressing the cam-lever B the plate, which is held apart by 30 the cam b' , acts to throw the lever down and the jaws of the clasp are brought firmly and evenly together upon the cloth, the projections on the jaws holding the material. As soon as the cam-lever B has closed, the pin b^4 then enters 35 the perforations a^8 and perforates the cloth, and also enters the puncture a^9 , which extends so far upon the opposite side as to prevent the exposure of the sharp point of the pin. To enable the strain upon the cloth to 40 draw the jaws of the clasp more firmly together, I make the teeth a^7 incline at an angle toward the ears a^2 a^3 on the upper and lower jaws, as seen in Fig. 5.

The jaws of the clasp A being attached to 45 the underwear, the button C is attached to the cuffs, and as the clasp cannot slip in any manner, no wear upon the cloth is occasioned and only the slight puncture of the cloth is seen.

As seen in Fig. 4, the clasp may be attached

directly to a suspender, and in Fig. 5 I have 50 designed the clasp to support the garments upon the person, the rivet a^4 passing directly through the button C and attaching said button to the plate a . In the form shown in Fig. 5 the end of the plate a of the clasp extending 55 from the pivot a^4 to the rear end of the jaws is curved outwardly and given the proper temper of a spring.

In Fig. 1 the plate a' or base may be made 60 rigid, if preferred, and the plate a tempered, if desired, to the proper degree to release the cloth.

When the lever B is thrown down upon the spring-plate and the pin is in the perforations a^8 a^9 , the said plate a is bearing upon the shoulders b' of the cam at an acute angle, and not only acting to close the jaws of the clasp, but also to keep the cam-lever pressed hard against the plate a .

I claim—

1. A clasp consisting of an upper spring-contracted bent plate and a lower plate suitably connected together at one end and having opposite parallel grip-jaws on their opposite ends, and a cam-lever pivoted to said lower 75 plate, said lever adapted to throw the jaws apart when elevated and to clasp upon said upper plate and jaw when depressed, substantially as described.

2. In a clasp, the combination of an upper 80 spring-contracted bent plate provided with a longitudinal slot and a lower plate, said plates being suitably connected together at one end and provided with respective upper and lower grip-jaws upon their opposite ends, and a pin-receiving perforation in said upper jaw, a cam pivoted to said under plate beneath said slot and adapted to throw apart said jaws, and a lever attached at one end to said cam, extending through said slot, adapted to clasp upon said 85 upper plate when depressed, and provided with a pin upon its opposite end for entering said perforation, as described.

EDWARD C. JONES.
